CLAIM

The ornamental design for a urine collection device as shown and described.

DESCRIPTION

FIG. 1 is a front, bottom perspective view of the claimed design of the urine capture device;

FIG. 2 is a front, top perspective view of the claimed design of FIG. 1;

FIG. 3 is a rear, bottom perspective view of the claimed design of FIG. 1;

FIG. 4 is a rear, top perspective view of the claimed design of FIG. 1;

FIG. 5 is a bottom view of the claimed design of FIG. 1;

FIG. 6 is a top view of the claimed design of FIG. 1;

FIG. 7 is a left side view of the claimed design of FIG. 1;

FIG. 8 is a right side view of the claimed design of FIG. 1;

FIG. 9 is a front side view of the claimed design of FIG. 1; and,

FIG. 10 is a rear side view of the claimed design of FIG. 1.

The ornamental design which is claimed is shown in solid lines in the drawings. The broken lines in the drawings are for illustrative purposes only and form no part of the claimed design.

The catheter is shown with a symbolic break in its length. The appearance of any portion of the article between the break lines forms no part of the claimed design.

1 Claim, 8 Drawing Sheets
